UNITED STATES PATENT OFFICE.

FRANK J. ROFFEIS, OF HELENA, MONTANA.

ENVELOP FOR BURNING TOBACCO.

1,339,577.

Specification of Letters Patent. Patented May 11, 1920.

Application filed March 31, 1917. Serial No. 158,888.

To all whom it may concern:

Be it known that I, FRANK J. ROFFEIS, a citizen of the United States, and a resident of Helena, in the county of Lewis and Clark 5 and State of Montana, have invented a certain new and useful Improvement in an Envelop for Burning Tobacco, of which the following is a specification.

The present invention relates to tobacco 10 users' appliances and more particularly to envelops or cases for cigars, pipes and the like.

An object of the present invention is to provide a pocket case adapted to receive 15 therein a burning cigar, or a lighted pipe; to prevent the heat of the cigar or pipe from burning the clothing; and to prevent ashes and tobacco from the cigar and pipe accumulating in the clothing.

20 The invention also aims at the provision of a suitably formed case or envelop for a cigar or a pipe having a heat insulating wall of non-combustible material to not only prevent contact of the burning tobacco with 25 the clothing, but also to prevent injury by heat radiation through the casing.

A further object of the invention is to provide an envelop or casing which embodies these novel features, and which will 30 also protect the cigar or pipe, and prevent access of air thereto.

The above, and various other important 35 novel features of the present invention will be in part described, and in part understood, from the following detailed description of the present preferred embodiment thereof, the same being illustrated in the accompanying drawings wherein:

Figure 1 is an inner side elevation of a 40 casing or envelop for cigars constructed according to the present invention.

Fig. 2 is a transverse section through the same taken on the line 2—2 of Fig. 1.

Fig. 3 is a plan view of a slightly modified 45 form of casing constructed according to the present invention and adapted to receive a pipe therein, the view showing the casing in open position.

Fig. 4 is a vertical longitudinal section 50 taken through a further modified form of the casing.

Fig. 5 is a vertical transverse section through the same, on the line 5—5 of Fig. 4.

Fig. 6 is a horizontal transverse section 55 taken through the casing of Fig. 4 on the line 6—6 thereof.

Fig. 7 is a plan view of the device in open position, showing a further modified form of the invention in open position.

Fig. 8 is a longitudinal section taken 60 through a still further modified form of the envelop.

Fig. 9 is a transverse section of a further modified form of the invention, disclosing a simplified construction of the form shown 65 in Figs. 1 and 2.

Fig. 10 is a horizontal transverse section 70 of a further modification, disclosing a simplified construction of the form disclosed in Figs. 4, 5 and 6.

Referring to the drawings, wherein like parts are designated by similar numerals of reference throughout the several views, and referring first to Figs. 1 and 2, 10 and 11 75 designate a pair of complementary sections which are hingedly connected at one edge by means of hinges 12, or the like. The sections 10 and 11 are hollow, are open at their inner sides, and are adapted to be swung together about the hinges 12 to close the 80 open sides thereof and provide a complete housing or envelop. The marginal edges of the sections 10 and 11 are adapted to abut when the casing is closed, and the opposite free ends of the sections 10 and 11 are provided with registering longitudinal concavities of substantially semi-cylindrical formation, as shown at 13, and partition walls 14, define the inner longitudinal sides of the concavities 13 and are substantially 85 flush with the top and bottom of the sections 10 and 11. When the sections 10 and 11 are closed, the partitions 14 abut, and close the end cylindrical compartment to the remaining interior of the casing. 95

This end compartment in the casing is of a size adapted to receive a lighted cigar therein, and the inner walls of the outer end concavities 13 are provided with a lining 15 of non-combustible heat-insulating 100 material, such as asbestos, to prevent burning of the casing sections 10 and 11 and to also prevent radiation of heat from burning cigars which may be placed in this end compartment. In the lower end of 105 one of the concavities 13 may be placed a pouch or pocket 16 which as shown, extends throughout substantially one-third of the length of the concavity 13 and is of a size adapted to receive one end of 110 a cigar therein. This pocket or pouch 16 is adapted to retain the cigar in the con-

cavity during the opening and closing movements of the sections 10 and 11, and to prevent the scattering of ashes and burning tobacco in handling the casing.

5 In the modified form shown in Fig. 3, the sections 10^a and 11^a of the case conform in shape substantially to the opposite sides of a pipe, and are hingedly connected together at one edge by hinges 12^a in substantially 10 the usual manner. The inner walls of the sections 10^a and 11^a are covered by a lining 15^a, preferably in the bowl-receiving portion of the case, the lining 15^a comprising a non-combustible heat insulating material. The 15 remaining, or stem portions, of the case may be provided with a suitable cloth or plush lining 17 in the usual manner.

In Figs. 4, 5 and 6 of the drawings, the sections 10^b and 11^b are in the form of 20 relatively deep pockets open at one end and adapted to be interfitted in telescoping relation. The section 10^b is provided in one end with a partition wall 14^b spaced inwardly a short distance from the adjacent 25 end wall of the section to provide a cigar-receiving pocket or compartment. The inner wall of this compartment is provided with a lining 15^b of non-combustible heat-insulating material adapted to receive thereagainst 30 hot ashes and burning tobacco, and prevent the radiation of the heat therefrom through the casing.

The partition wall 14^b projects a short distance upwardly from the open end of the 35 section 10^b and is adapted to engage the inner side of the end wall of the opposite section 11^b. The partition wall 14^b is of such width as to completely close the end compartment to the interior of the casing and to 40 thus confine the ashes and burning tobacco to the compartments. To insure this result, the inner closed end of the section 11^b is provided with a non-combustible heat-insulating lining 18 extending over the end wall 45 thereof and along the sides of the section 11^b to a depth equal to the projecting end of the partition 14^b. Such a construction admits of the placing of the section 11^b upon the section 10^b with either end of the former 50 in registry with the heat-insulated compartments.

In the modified form shown in Fig. 7, the complementary sections 10^c and 11^c are hingedly connected at one edge by hinges 12^c, and are formed to the configuration of the opposite sides of a cigar. The sections 10^c and 11^c when closed meet at their marginal edges and completely cut off access of air to the interior of the case. 60 The inner walls of the sections 10^c and 11^c are covered by a non-combustible heat-insulating lining 15^c.

In the form shown in Fig. 8, the casing is composed of a pair of tubular sections 10^d 65 and 11^d conforming to the opposite ends of

a cigar. One of the sections, such as the section 11^d, is provided with a slightly reduced open end portion or neck 19 adapted to frictionally engage in the open end of the opposite section. The inner walls of the sections 10^d and 11^d are provided with a non-combustible heat-insulating lining 15^d to prevent radiation of the heat from a lighted cigar which is placed in the casing, and to prevent injury to the casing if formed 70 of combustible material. When this latter form of case is used, one end of a cigar, which may be burning, is inserted in one of the sections, and the opposite section is then fitted over the opposite end of the cigar and 75 forced upon the opposite section. The neck 19 provides an air-tight joint which prevents access of air to the burning cigar, and the latter is in a short time extinguished. 80

In all forms of the invention, it is readily 85 noted that the burning charge of tobacco, whether in cigar form, in a pipe bowl, or in other desired form, is placed in the case, the non-combustible lining will prevent the burning tobacco from setting fire to adjacent objects, or to the walls of the case. In each form, the heat-insulating lining retains the heat of the burning tobacco in the compartment of the case and prevents the 90 radiation thereof through the walls of the 95 case and to the pocket or surrounding objects.

When the forms shown in Figs. 1 and 2 is used, one end of the cigar may be inserted in the pocket or pouch 16, and the 100 cigar is held in place in the concavity of the section so that when the sections are swung into open and closed positions, the cigars cannot be readily dislodged, and the ashes 105 cannot be scattered. In referring to a fire-proof lining, it is to be understood that asbestos, or any suitable material may be employed, or the interior walls of the case may be coated with a suitable substance for carrying out the object of this invention. 110

The form illustrated in Fig. 9 is similar to that shown in Figs. 1 and 2 with the exception that the compartment for fresh cigars is not provided with the corrugations or the individual recesses for holding the 115 cigars separated. In this instance, the sections 10^e and 11^e are provided with relatively flat sides, and the section 10^e may be provided with a flap 20 which is looped outwardly from the section 10^e, and which may 120 extend to any desired height at the inner side of the same. The flap 20 is adapted to hold any desired number of cigars or the like in the section 10^e and in position to be enclosed in the case when the sections 10^e and 11^e are swung together. The partition walls 14^e may be formed from separate metallic strips as shown which are bent and curved into substantially rectangular form and 125 soldered or otherwise suitably secured against 130

the inner sides of the sections 10^e and 11^e in position to register when the sections are closed to thus form the end compartment.

5 The form disclosed in Fig. 10 comprises telescoping sections 10^f and 11^f which are provided with relatively flat or straight opposite sides so that any desired number of fresh cigars or the like may be crowded in 10 the case. The partition 14^f is relatively wide and bears at opposite edges against the inner walls of the inner section 10^f to close the large compartment from the small end compartment. In other respects, the 15 form of the device shown in Fig. 10 is similar to that disclosed in Figs. 4, 5 and 6.

It is of course understood that various other changes and modifications may be made in the details of construction of the

above-described embodiment of this invention without departing from the spirit thereof, and being restricted only by the scope of the following claim.

I claim:—

A case for cigars and the like including 25 a pair of complementary sections adapted to fit together and provided with partitions to form spaces therein for accommodating a supply of cigars or the like and a compartment in one portion of the case cut off from 30 the remainder of the interior of the case and from the spaces occupied by said supply of cigars or the like, said cut off compartment adapted to receive a lighted cigar or the like, and a lining of refractory and 35 heat insulating material placed in said compartment.

FRANK J. ROFFEIS.
